2 SHEETS—SHEET 2.

UNITED STATES PATENT OFFICE.

GEORGE H. SCANLAN, OF NEW YORK, N. Y.

TRACTOR-ENGINE.

1,370,844.

Specification of Letters Patent.

Patented Mar. 8, 1921.

Application filed September 20, 1919. Serial No. 325,126.

To all whom it may concern:

Be it known that I, GEORGE H. SCANLAN, residing at New York, in the county and State of New York, have invented certain new and useful Improvements in Tractor-Engines, of which the following is a specification.

This invention relates to an engine, and particularly to an engine of the explosive type, such as may be used for tractors and the like.

An object of the invention is to provide an engine having its several parts so simplified and correlated that the number of parts may be maintained at a minimum and without sacrifice of efficiency, the present invention being adaptable for use in a tractor such as that shown and described in my Patent 1,324,694, Dec. 9, 1919.

A further object is to provide an engine of the kind indicated and including a valve operating shaft having direct spiral gear connection for driving an electric generator or magneto device which may be connected for supplying electric energy for the spark plug or plugs of the engine, also for operating the engine fan.

A more detailed object is to provide a mechanism of the type indicated and including one or more tractor wheels, together with connections for driving said wheels, and to provide a valve operating shaft arranged to be operated by said connections and having direct gear engagement with a drive shaft for a generator or magneto device, so that said generator or magneto device, as well as the fan, is adapted to be operated through the least possible number of parts.

A further and more detailed object is to provide an engine including the usual piston and crank shaft, a gear fixed to rotate with the crank shaft, a second gear engaging the first gear to be rotated thereby, one or more traction wheels arranged to be driven by said second gear, valve operating means also arranged to be driven by this second gear, and an electric generator or magneto device connected to be driven by said valve operating means.

Other objects and aims of the invention, more or less specific than those referred to above, will be in part obvious and in part pointed out in the course of the following description of the elements, combinations, arrangements of parts and applications of

principles, constituting the invention, and the scope of protection contemplated will be indicated in the appended claims.

In the accompanying drawings which are to be taken as a part of this specification, and in which I have shown merely a preferred form of embodiment of the invention:

Figure 1 is a vertical sectional view of an engine constructed in accordance with this invention, parts being shown in full lines.

Fig. 2 is a vertical sectional view taken at right angles to the view, Fig. 1, the section being taken substantially on the plane of line II-II of Fig. 1,

Fig. 3 is horizontal sectional view taken substantially upon the irregular plane indicated by the line III-III of Fig. 1, and

Fig. 4 is a fragmentary detail view illustrating the manner of supporting the fan shaft.

Referring to the drawings for describing in detail the structure illustrated therein, the reference character L indicates the engine cylinder. While of course there may be any number of cylinders only one such is illustrated.

The crank shaft, as 1, is mounted within bearings 2 provided at opposite sides of a casing 3, which casing depends below the engine cylinder. The crank shaft is connected with the engine piston in the usual manner, as at 4, so that the reciprocations of the piston will produce rotation of the shaft.

Fixed to the shaft, and preferably within the casing 3, is arranged a small pinion 5 the teeth of which mesh with the teeth of a large gear 6 carried upon a shaft 7 disposed parallel to the crank shaft 1 and supported in bearings 8 on opposite sides of the casing. The end portions of the shaft 7 project beyond the casing and carry fixed thereto small pinions 9, the teeth of which engage the teeth of the internal gears 10 of the traction wheels G.

In this manner the power from the shaft 1 is greatly multiplied in being transmitted to the traction wheels.

The traction wheels G may be mounted in any desired manner, either concentrically of the crank shaft 1 or otherwise, as may be preferred, or they may be mounted adjustably after the manner suggested in my pending application above referred to.

The valve rods, as 11, for the engine are

mounted to be operated by cams 12 which are fixed to a shaft 13. This shaft is also mounted in bearings at opposite sides of the casing and it extends parallel to the 5 drive shaft 1, the bearings being indicated at 14. For driving the shaft 13 a gear 15 fixed thereto engages the teeth of the gear 6.

It will be noted that each of the gears thus far described are simple spur gears all 10 mounted upon shafts extending in parallel relation to each other so that maximum efficiency and simplicity are at once obtained with respect to the parts to which these gears are related.

15 The generator, or magneto device, as H, is adapted to be operated by a shaft 16 which extends in a direction at right angles to the shafts heretofore mentioned, and it is an essential feature of this invention 20 to provide the simple and direct means as illustrated for driving this shaft 16. This means includes disposing the shaft 16 so that a portion of its length traverses directly beneath a portion of the valve operating shaft 25 13, and in providing these said two shafts with intermeshing helical gears 17 and 18. The spiral gears may, of course, be of any relative proportions to each other according to the speed of rotation which it is desired 30 shall be imparted to the shaft 16 from the shaft 13. Or the pitch of the gears may be modified to the same purpose.

It will thus be seen that the only elements 35 of mechanism which are provided for operating the generator shaft are the two gears 17 and 18. No other gears, shafts or other contrivances are present or required. Yet the arrangement is one of extreme simplicity and entire practicability.

40 As is clearly illustrated in the drawings Figs. 1 and 4, the generator shaft is also adapted for driving the engine fan. For this purpose the generator shaft is fitted with a drive pulley 19 about which engages 45 the fan belt 20 through which power is transmitted from the generator shaft to the pulley 21 on the fan shaft 22. The pulley 21 is fixed at one end of the fan shaft and the fan 23 is fixed at the opposite end, the 50 shaft being supported intermediate its length within a bearing 24.

In this way the simple driving connections, as described, for driving the generator shaft, are also adapted for driving the 55 fan, the connections serving with equal efficiency and practicability for both these purposes.

It is a further feature of this invention to utilize the portion of the casing, as 60 25, which surrounds the gear 6 as a support for a breather pipe 26 and to dispose this breather pipe in such relation to the fan shaft that the bearing piece 24 carrying the fan shaft may be readily mounted upon the 65 breather pipe in a manner so that adjust-

ment of the fan shaft with respect to the shaft 16 may be readily and easily accomplished. In carrying out this object it will be seen that the bearing piece 24 is formed at one end of an arm 27, the opposite end of 70 which is shaped to constitute a clamp element 28 fitted about the breather pipe 26. By simple manipulation of the clamp screw 29 the fan shaft may thus be moved along the length of the breather pipe for regulating the tension of the fan belt.

By arranging all of the several parts and features as shown and as above described, a very compact result is obtained while at the same time ample provision is afforded for 80 conveniently reaching the different parts as occasion may require. For instance, it will be noted that by employing a direct spiral gear connection between the valve shaft and the shaft 16, and by thereby avoiding the 85 use of additional shafts and gears which would necessarily occupy much of the space now given to the breather pipe and fan parts, said space is left entirely free of any obstruction so that the breather pipe and 90 fan parts are admirably positioned both for simplicity and efficiency of operation and for convenience of manipulation whenever occasion should require readjustment of these parts.

95 The breather pipe may also be conveniently utilized as a support for the fuel tank 30. As illustrated, the tank 30 is fixed to the upper end of the breather pipe by means of a clamp device 31.

100 As many changes could be made in this construction without departing from the scope of the invention as defined in the following claims, it is intended that all matter contained in the above description or 105 shown in the accompanying drawings, shall be interpreted as illustrative only and not in a limiting sense.

Having thus described my invention, what I claim as new and desire to secure by 110 Letters Patent is:—

1. In a tractor engine, comprising a cylinder having the usual valve and valve operating shaft, a radiator fan, an electric generator device, a shaft for driving said fan and generator device, and driving connections whereby said valve shaft is made to drive said second shaft and to drive through said second shaft said fan and said generator device, the combination therewith of a 115 pair of tractor wheels, and drive means for said valve shaft and wheels comprising a drive shaft extending between said wheels and geared thereto and to said valve shaft.

120 2. In a tractor engine, comprising a cylinder having the usual valve and valve operating shaft, a radiator fan, an electric generator device, a shaft for driving said fan and generator device, and driving connections interengaging between an end portion of 125

said valve shaft and said second shaft at one side of said cylinder whereby said valve shaft is made to drive said second shaft and to drive through said second shaft said fan and said generator device, the combination therewith of a pair of tractor wheels, and drive means for said valve shaft and wheels comprising a shaft extending between said wheels being geared at its ends with said 10 wheels, connections between the engine and said wheel driving shaft comprising in part a gear carried by said wheel driving shaft, and a further gear meshing with said last mentioned gear and being fixed to the valve 15 operating shaft at the opposite side of the cylinder.

3. In a tractor engine, the combination comprising a cylinder having the usual crank shaft and valve operating shaft extending parallel with said crank shaft, of a 20 pair of traction wheels, bearings for said crank shaft having parts serving as axles for said traction wheels, a shaft spaced from said crank shaft parallel therewith being 25 geared by its opposite ends with said traction wheels to drive said traction wheels, a pinion gear carried by the crank shaft, a large gear carried by said wheel driving shaft meshing with said pinion gear, a gear

fixed to said valve operating shaft and 30 meshing with said large gear, said three mentioned gears being disposed in a plane at one side of the cylinder, an electric generator device, a shaft arranged at the opposite side of the cylinder extending at right 35 angles to all said mentioned shafts, being connected with said generator device, and helical gear connections between said last mentioned shaft and said valve shaft.

4. In a tractor engine, comprising a cylinder having the usual valve and valve operating shaft, a radiator fan, an electric generator device, a shaft for driving said fan and generator device, and driving connections whereby said valve shaft is made to drive 40 said second shaft and to drive through said second shaft said fan and said generator device, the combination therewith of a tractor wheel, and drive means for said valve shaft and wheel comprising a drive shaft 50 geared to said wheel and to said valve shaft.

In testimony whereof I affix my signature in the presence of two witnesses.

GEORGE H. SCANLAN.
